PORTABLE HAIRDRYER CASING

Douglas N. Cabell, Birmingham, Mich., assignor to Ronson Corporation, Woodbridge, N.J., a corporation of
New Jersey

Filed Sept. 28, 1965, Ser. No. 87,207

Term of patent 14 years

(Cl. D86—10)

FIG. 1

FIG. 2

FIG. 3

FIG. 1 is a front view of a portable hairdryer casing showing my new design.

FIG. 2 is a top plan view thereof.

FIG. 3 is a bottom plan view thereof.

FIG. 4 is a side elevational view thereof; and

FIG. 5 is a rear elevational view thereof.

I claim:

The ornamental design for a portable hairdryer casing, substantially as shown.
